UNITED STATES PATENT OFFICE.

LINNAEUS E. BAKER, OF FORT WAYNE, INDIANA, ASSIGNOR TO WAYNE OIL TANK & PUMP CO., A CORPORATION OF INDIANA.

DISPENSING-PUMP.

1,247,203.

Specification of Letters Patent. Patented Nov. 20, 1917.

Application filed May 28, 1915. Serial No. 30,878.

To all whom it may concern:

Be it known that I, LINNAEUS E. BAKER, a citizen of the United States of America, and resident of Fort Wayne, in the county 5 of Allen and State of Indiana, have invented certain new and useful Improvements in Dispensing-Pumps, of which the following is a specification.

This invention relates to improvements in 10 pumps for dispensing oil and other liquids, and the object thereof is to provide a crank operated pump with mechanism intervening between the crank and the pump-rod by means of which the latter will be reciprocated as the crank is turned continuously in one direction only, and a further object is to construct the intervening mechanism with gearing by means of which the ratio of movement between the crank and the pump-rod 15 will vary so that during the upward or discharge stroke of the pump the leverage of the crank in its operation of the pump rod through the gearing will be comparatively greater than when the pump-rod is moved in the opposite direction. By this 20 construction the amount of physical energy required to operate the crank throughout the cycle of movement of the pump is more nearly uniform and a further advantage of the rapid return of the pump plunger is attained after having made the discharge 25 stroke which latter requires comparatively greater force. The idea of the invention is to apply through the mechanism sufficient 30 leverage in lifting the plunger during the suction and discharge stroke as to render the operation easy, and to effect the return stroke of the pump plunger quickly and without the necessity of reversing the movement of the operating crank. By means of 35 the construction herein disclosed the complete operation of the pump is effected by turning the crank continuously in one direction at uniform velocity, the plunger being lifted in its discharge stroke with comparatively greater force while its return stroke is effected with comparatively greater velocity.

Another feature of the invention is the provision of mechanism by means of which 40 the gearing for operating the pump-rod may be shifted so as to effect the reversal of movement of the pump plunger at any desired stage.

The objects of the invention are accomplished by the construction illustrated in 55 the accompanying drawings in which:

Figure 1 is a vertical central section of the device;

Fig. 2 is an elevation of the device in a plane at right angles to Fig. 1 and with the 60 pedestal shown in section;

Fig. 3 is an enlarged detail view of the driving head in the same plane as Fig. 1;

Fig. 4 is an enlarged detail view of the driving head in section on the line —C of 65 Fig. 1;

Fig. 5 is an enlarged detail view of a part of the clutch shifting mechanism, in section on the line —D of Fig. 1;

Fig. 6 is an enlarged detail view of the 70 clutch shifting mechanism, in section on the line —F of Fig. 4;

Fig. 7 is a detail view showing the clutch controlling mechanism in its position when the back gear is used;

Fig. 8 is a similar view of the same showing it in position when the direct gear is used;

Fig. 9 is a plan view of the apparatus showing a transverse section through the 80 driving head on the line —E of Fig. 1; and

Fig. 10 is a vertical central section through the top of the head of the pump cylinder.

Similar numerals of reference indicate 85 corresponding parts throughout the various views and referring now to the same:

The invention is comprised of a pump proper and a mechanism for actuating the pump, and also a stop mechanism for regulating the actuating mechanism. The pump proper is comprised of a cylinder (1) having a chambered-head (2) at its top and a head (3) at its lower end containing an inlet valve (4). Within the cylinder is a 90 reciprocating plunger (5) having a valve (6) that admits of the passage of liquid through the plunger upon the return stroke thereof. The valve (4) is seated so that as the plunger is raised liquid will be drawn 95 into the lower part of the cylinder through the pipe connection (7) and will be prevented from retracting by said valve during the return stroke of said plunger. The valve (6) in the plunger is seated so as to 100 allow the liquid drawn into the lower part

of the cylinder to pass through the plunger during the return stroke of the plunger and to prevent retraction of the liquid in the upper part of the cylinder through the 5 plunger, it being the intention that as the plunger is raised, the liquid in the upper part of the cylinder after having passed through the plunger will be forced by the upward movement of the latter into the 10 chamber (8) of the head (2) from whence it is expelled through the discharge pipes (9) and (10) which communicate respectively with said chamber.

One of the features of the invention consists in the cylindrical screens (11), made 15 of gauze or perforated material, that are attached to removable plugs (12) that are screwed into the head (2) so that the screens extend into the chamber (8) thereof. The discharge pipes (9) and (10) have 20 screw threaded connection respectively with the plugs (12) through which they communicate with the chamber (8), the screens serving to strain the liquid as it leaves the 25 chamber and passes into the discharge pipes.

The pump has a pump-rod (13) connected with the plunger (5) and which extends up through a stuffing-box (14) in the head (2). The pump thus formed is supported upon a 30 cylindrical pedestal (15) the outer marginal head of the pump resting upon the top of the pedestal and secured thereto by means of cap-screws (16).

The mechanism for actuating the pump 35 is supported upon the head (2) and consists of a standard (17) having a housing (18) at its upper end through which the pump-rod (13) extends, and a pipe (19) secured in the head (2) and that has communication 40 at its lower end with the chamber (8) extends up through a lug (20) that projects from the side of the housing and affords support for same. A cap (21) closes the 45 top of the pipe (19) so as to prevent the discharge of fluid, the pipe serving as an expansion chamber as well as support for the housing.

A rack-bar (22) is fixed upon the pump-rod (13) and has near its lower end a horizontally projecting lug (23). A crank-shaft 50 (24) extends through the housing and has a crank (25) fixed upon its outer end for operating the same, and also upon said shaft, within the housing are loosely mounted two clutch-wheels (26) and (27) the hubs of which are toothed to form pinions (28) and (29) respectively. The pinion (28) engages in mesh with the rack-bar (22), and the pinion (29) engages in mesh with a back gear (30) which is fixed upon a counter-shaft (31), the latter extending in parallel 60 relation with the crank-shaft (24) and being supported at its respective ends in the housing. Also fixed upon the shaft (31) is a pinion (32) that engages in mesh with the

rack-bar (22). Fixed upon the crank-shaft (24), and intervening between the clutch-wheels (26) and (27) is a block (33) upon which is mounted a ratchet-wheel (34), the latter being adapted to be shifted longitudinally upon the block so that the teeth (35) on one of its ends may engage the clutch-wheel (27), or the teeth (36) upon its opposite end may engage the clutch-wheel (26) accordingly as the ratchet-wheel (34) is shifted from one position to the other. An annular groove (37) is made in the ratchet-wheel into which extend pins (38) that project from a yoke (39) at the end of its arms (40). The yoke is mounted loosely upon a shaft (41), the latter extending through its arms. Fixed upon the shaft (41), adjacent the yoke (39) is an arm (42) having a counter-sunk opening (43) therein adapted to receive the pointed end of a plug (44) that is loosely mounted in the yoke and pressed by means of a spring (45) into contact with the arm (42), the spring being mounted in the yoke. The shaft (41) is adapted to be oscillated so that the yoke will be caused to 70 shift the ratchet-wheel into engaging relation with one or the other of the clutch-wheels (26) or (27), movement being applied to the yoke through the medium of the arm (42) and its engagement with the plug (44). The pointed plug (44) bearing in the counter-sink in the arm (42) affords yielding connection between the arm and yoke so that the latter will move with the 75 shaft (41) as it oscillates, and thus causing the ratchet-wheel to be yieldingly pressed into engagement with the corresponding clutch-wheel. Should the crank (25) be revolved in the opposite direction to its driving movement, the ratchet-wheel will tend to drift from its connection with the clutch-wheel with which it is engaged because of the slant of its teeth and the yoke will accommodately swing upon the shaft (41), the plug (44) being forced inwardly against 80 the pressure of the spring (45) to admit of the necessary play of the yoke upon the shaft. As the pointed end of the plug tends to center in the counter-sink in the arm (42) the yoke tends to hold the ratchet-wheel into 85 engagement with one or the other of the clutch-wheels according to the position of the arm (42). Thus, as the shaft (41) is rotated, the ratchet-wheel, while pressed against the face of one or the other of the clutch-wheels by the yoke so that the engaged clutch-wheel will be driven as the 90 crank is operated in one direction, will be permitted to drift from its toothed engagement with the clutch-wheel and rotate idly 95 when the movement of the crank-shaft is reversed. It is essential that the drift of the teeth on the respective ends of the ratchet-wheel is such that the clutch-wheel has to engage and drive the corresponding 100 105 110 115 120 125 130

clutch-wheel when rotated normally in the driving direction. By this construction it will be noted that as the ratchet-wheel (34) is in engagement with the clutch-wheel (27) 5 and the crank (25) is revolved in the direction of the movement of the hands of a clock, the clutch-wheel (27) and the pinion (29) moving therewith will likewise be revolved and the back-gear (30) meshing with the pinion will become rotated in the opposite direction, which being fixed upon the shaft (31), will cause the pinion (32), also fixed upon the same shaft, to likewise revolve, causing the rack-bar (22) meshing 10 therewith to move upwardly. As the rack-bar is moved the pump-rod and plunger connected therewith are accordingly actuated.

When the ratchet-wheel (34) is shifted into engagement with the clutch-wheel (26) 20 the pinion (28) connected with the latter and engaged in mesh with the rack-bar (22), upon rotation of the crank-shaft (24), drives the rack-bar downwardly, thus effecting the return stroke of the plunger. It will be noted that in the latter action the 25 return stroke is effected through the rotation of the crank-shaft and pinion (28) which latter acts directly upon the rack-bar, and it will also be noted that when the 30 ratchet-wheel engages the clutch-wheel (27), the rack-bar will be actuated upwardly through the medium of the pinion (29), back-gear (30) and pinion (32).

It is essential to shift the ratchet-wheel 35 from engagement with one clutch-wheel to the other, in order to effect the reversal in the driven movement of the rack-bar without reversing the direction of the rotation of the crank, it being the intention to operate the mechanism by revolving the operating crank in one direction only. In order 40 to effect the shifting of the ratchet-wheel from engagement with one clutch-wheel to the other at the ends of the discharge and return strokes of the pump, a mechanism is 45 provided consisting of a vertically movable rod (46), the lower end of which extends loosely into a lug (47) on the head (2), and the upper end of which has fixed thereon a 50 rack-bar (48), the latter extending through the housing and engaging a toothed segment gear (49).

An oscillating shaft (50) extends through 55 the housing in parallel relation with the shaft (41) and the segment gear (49) is fixed thereon so that as the rod (46) with the rack-bar (48) is moved vertically the shaft (50) is accordingly oscillated. Upon 60 the outer ends of the shafts (41) and (50) are rigidly fixed bifurcated levers (51) and (52) respectively, shown in Figs. 3, 7 and 8. The innermost arm (53) of the lever (51) has a laterally projecting block (54) upon 65 its outer face, and the outer arm (55) of the lever (52) has a similar laterally projecting

block (56) upon its inner face, the said blocks extending in a common plane so that they may come into contact with each other when the levers are oscillated. The inner arm (57) of the lever (52) is extended forwardly so as to serve as a handle for the purpose of manual manipulation, and the rear end of the inner arm (58) of the lever (51) is provided with extending feet (58) that are adapted to alternately come into 70 contact with the adjacent wall (59) of the housing as the lever is shifted from one of its positions to the other and thus limit the range of movement of the lever. Each of the levers (51) and (52) has a spud (60) 75 that extends through each of its arms in parallel relation with the corresponding shafts (41) and (50), and a rod (61) extends through both spuds at points intervening between the arms of the levers. A 80 nut (62) is fixed at the top of the rod that limits the relative downward movement of the rod by coming into contact with the adjacent spud. A nut (63) fixed upon the rod is adapted to bear downwardly against the 85 spud (60) in the lever (51) when the rod (61) is accordingly pressed. A nut (64) also fixed upon the rod (61) affords a seat for one end of a compression-spring (65) that bears upwardly against the spud (60) in 90 the lever (52), and another nut (66) fixed at the lower end of the rod serves as a seat for the lower end of a compression spring (67) that bears upwardly against the spud (60) in 95 the lever (51). When the shaft (50) 100 is oscillated by the vertical movement of the rod (46) the lever (52) is accordingly swung upwardly or downwardly. When the lever is swung upwardly, the rod (61), because of the engagement of the nut (62) thereon with 105 the spud (60) in said lever, is drawn upwardly and the spring (67) between the nut (66) and spud (60) in the other lever (51) becomes compressed so that it tends to swing the lever (51) upwardly. As the lever (52) 110 is being swung upwardly, the upward pressure of the spring (67) increases and tends to swing the lever (51) upwardly and the latter is detained from responding to the pressure of the spring because during the 115 upward movement of the lever (52), the block (54) carried by the lever (51) becomes obstructed by the block (56) on the lever (52) and its upward swinging movement is thereby prevented until the lever (52) has moved to a point where its block (56) is carried out of the path of the block (54) on the other lever (51) (as shown in Fig. 7), at which stage the lever (51) is pressed to its uppermost position and the shaft (41) accordingly oscillated with the effect that the ratchet-wheel (34) becomes shifted from the clutch-wheel (27) to engagement with the clutch-wheel (26). Thus the driving 125 relation of the crank with the pump-rod becomes 130

reversed and its ratio of driving action reduced.

When the lever (52) is moved downwardly by the corresponding downward movement 5 of the rod (46) the spring (65) becomes compressed against the nut (64), and the rod (61) therefore is pressed downwardly so that the nut (63) acts to press the lever (51) downwardly. During the downward 10 movement of the lever (52) the block (54) carried by the lever (51) becomes obstructed by the block (56) of the lever (52), and its downward swinging movement is thereby prevented until the lever (52) has moved 15 to a point where its block (56) is carried out of the path of the block (54) on the other lever (as shown in Fig. 8) at which stage the lever (51) is pressed to its lowermost position and the shaft (41) accordingly 20 oscillated with the effect that the ratchet-wheel (34) becomes shifted from the clutch-wheel (26) to engagement with the clutch-wheel (27). Thus the driving relation of the crank with the pump-rod becomes 25 reversed and its ratio of driving action increased. The rotation of the crank continuously in one direction effects the continuous reciprocation of the pump with a high ratio of action between the crank and the 30 pump during the upward or discharge stroke thereof and a comparatively lower ratio during the return stroke.

As a means of automatically effecting the shifting of the ratchet-wheel so as to reverse the action of the gearing at each end 35 of the stroke of the pump, two stops (68) and (69) are secured respectively upon the rod (46) near its opposite ends so that the projecting lug (23) on the rack-bar will intervene therebetween and engage the stop 40 (69) upon the upward stroke of the rack-bar (22), causing the rod (46) to be moved upwardly; and engage the stop (68) upon the downward stroke of the rack-bar (22) 45 causing the rod (46) to move downwardly. Thus the gearing hereinbefore described in train between the crank and the pump-rod becomes reversed at each end of the stroke 50 of the pump and with the accompanying alteration in the ratio of movement. The rod (70) is fixed in parallel relation with the rod (46) and extends loosely through the stops (68) and (69) so as to serve as a 55 guide for the stops and prevent the same from turning out of the path of the projecting lug on the rack.

The stops (68) and (69) are spaced at such distance apart as to cause the reversal of the driving gear at the respective ends of 60 the stroke of the pump to confine the length of the stroke of the pump to such extent that a predetermined definite quantity of liquid will be discharged upon each complete cycle of the pump.

65 As a means of causing the reversal of the

gearing to take place at other stages than at the complete strokes of the pump, so that fractional portions of the normal discharge from the pump may be effected, a series of adjustable stops (71) are threaded upon the rod (46) and spaced apart thereon at suitable intervals accordingly as to the extent of the movements of the pump is desired. The stops (71) are adapted to be severally turned upon the rod (46) as the operator 70 may desire into the path of the lug (23) on the rack-bar (22) so as to become engaged thereby during the upward stroke of the pump with the effect that the rod (46) becomes lifted at correspondingly intermediate 75 stages of the normal stroke of the pump. By properly spacing the stops (71) upon the rod, various definite predetermined quantities of liquid upon each cycle of the pump may be effected by shifting the stops 80 accordingly into the path of the engaging lug on the rack, the reversal being effected upon the engagement of the lug with the adjustable stop.

Adjustment is provided for confining the 85 swinging movement of the lever (52) to within its intended range, and the adjustment is comprised of set-screws (72) that extend through the housing (18) so as to contact respectively with the upper and lower 90 faces of the segment gear (49) as the latter is raised or lowered. By adjusting the set screws the play of the gear (49) and the consequent movement of the shaft (50), and lever (52) fixed thereon, is provided for so 95 that the block (56) carried by the lever (52) will be carried when the lever is in uppermost position clear of the path of the block (54) on the other lever, (as shown in Fig. 7) and when in its lowermost position (as 100 shown in Fig. 8) the block (56) will clear the path of the block (54) upon the opposite side, in each instance permitting the passage of the block (54) as the lever to which it is fixed is moved from one of its positions 105 to the other. When the lever (52) is moved downwardly pressure is exerted upon the lever (51) to move it downwardly also, but the latter is detained by the interference of the blocks (56) and (54) until the former lever has completed its stroke. Upon 110 the upward movement of the lever (52) pressure is exerted upon the lever (51) to move it upwardly also, but the latter is detained because of the interference of the 115 blocks until the former lever has completed its stroke. The movement of the lever (51) has the effect of shifting the ratchet-wheel from one clutch-wheel to the other so that 120 the driving relation of the crank with the pump-rod is reversed. When the rod (46) is raised by the upward stroke of the pump-rod, the segment gear (49) comes into contact with the upper set-screw (72) stopping the movement of the driving gear. By 125 130

a slight retracting movement applied to the operating crank sufficient slack is afforded to allow the ratchet-wheel to slip from its connection from the engaged clutch-wheel so as to become shifted into engagement with the other clutch-wheel as described. Upon the downward movement of the rod (46) the segment gear will contact with the lower set-screw (72) with similar effect.

10 The discharge pipes may extend to any suitable point for the delivery of liquid expelled by the pump therethrough and may also be provided with a faucet (73), or the discharge pipes may be connected with the head of the pump by means of a swivel connection (74) so that the faucet may be swung around from one position to the other. Or, for convenience, one of the discharge pipes may be extended to a suitable height above the apparatus and have a hose (not shown) attached thereto for conveying the discharge of the pump to receptacles as may suit the convenience of the operator. The chambered head (2) has an upwardly extending inner wall (75) and the opening (76) at the top of the wall for the admission of liquid from the cylinder into the chamber. The chamber is so proportioned as to contain therein the filter screens (11). A pipe (77) having a cock (78), extends through the head and communicates with the lower part of the chamber and is intended for the periodical discharge of sediment therefrom.

What I claim is:—

35 1. In apparatus of the class described, a reciprocating pump; a rack-bar fixed upon the pump-rod thereof; a standard in connection with the pump having a gear housing; a countershaft having a back-gear and pinion fixed thereon, the pinion meshing with the rack-bar; a crank-shaft having a block fixed thereon and two pinions loosely mounted thereon one upon each side of the block and engaged respectively in mesh 40 with the rack-bar and gear; a clutch-wheel in fixed relation with each of the latter pinions; a ratchet-wheel on the block adapted to selectively engage the clutch-wheels; an oscillating yoke having engagement with the 45 ratchet-wheel for shifting the same; and a stop-mechanism adapted to be engaged and actuated in opposite directions at the corresponding ends of the stroke of the rack-bar and having also actuating relation with the yoke.

50 2. In apparatus of the class described, a reciprocating pump having a pump-rod with a rack bar fixed thereon; two pinions engaging the rack; a reversing gear mechanism having actuating relation with said pinions adapted to actuate the rack in opposite directions through the medium of said pinions alternately; and means adapted to be engaged and actuated by the pumping mechanism in opposite directions as the

pump is reciprocated and having also actuating relation with the gear mechanism to reverse the same.

55 3. In mechanism of the class described, a reciprocating pump having a pump-rod with a rack-bar fixed thereupon; a reversible gearing having two pinions in driving relation with the rack-bar adapted to actuate the same in opposite directions through the medium of said pinions alternately; a stop mechanism adapted to be engaged and actuated by the rack-bar at the corresponding ends of its stroke; and means in connection with the stop mechanism and gearing for reversing the latter.

60 4. In apparatus of the class described, a reciprocating pump; a reversible gearing in connection with the pump to actuate the same; a stop mechanism; means in connection with the stop mechanism and gearing for reversing the latter as the stop mechanism is shifted; and means in connection with the pump adapted to engage and shift the stop mechanism in opposite directions at the corresponding ends of the stroke of the pump.

65 5. In apparatus of the class described, a pump; a rack-bar for actuating the pump; a shaft having a back-gear and pinion fixed thereon with the pinion meshing with the rack-bar; a shaft having a crank attached thereto to operate the same and having loosely mounted thereon two pinions, one in mesh with the rack-bar and the other with the back-gear; a clutch-wheel fixed on each of the latter pinions; a ratchet-wheel adapted to be driven by the crank-shaft and to selectively engage said clutch-wheels accordingly as shifted; an oscillating shaft having fixed thereon an arm, the latter having a counter-sink therein; a yoke loosely mounted on the oscillating shaft and with its arms having connection with the ratchet-wheel to shift the latter; a spring pressed pointed plug in the yoke with its pointed end extending into the counter-sink in said arm; a stop mechanism adapted to be engaged and actuated by the rack-bar in opposite directions at the corresponding ends of its stroke; and a mechanism in connection with the stop mechanism and the oscillating shaft to actuate the latter.

70 6. In apparatus of the class described, a reciprocating pump; a rack-bar in connection with the pump to actuate the same; a reversible gearing engaged with the rack-bar adapted to drive the same in opposite directions; a stop mechanism adapted to be engaged and actuated in opposite directions by the rack-bar at the corresponding ends of the stroke of the pump; a shaft having a segment gear actuated by the stop mechanism; a lever fixed upon said shaft; a second shaft having means in connection therewith for controlling said reversible gearing and

- having also fixed thereon a lever for actuating the same; a rod having sliding connection with each of the levers and having also two compression springs thereon bearing respectively against said levers; and a block on each lever, the one adapted to obstruct the movement of the other during the transit of the former lever from one of its positions to the other.
10. In apparatus of the class described, in combination with a reciprocating pump having a reversible gearing in connection therewith for actuating the same, an oscillating shaft having means in connection therewith for reversing said gearing and having also a lever fixed thereon for actuating the same; a second oscillating shaft having a lever fixed thereon, each of said levers having a projecting block extending in a common plane; a stop mechanism having connection with the pump actuating mechanism adapted to be driven in opposite directions thereby at the corresponding ends of the stroke of the pump and having means in connection also with the latter oscillating shaft to actuate the same; a rod having sliding connection with each of said levers; and two compression springs on the rod acting respectively against said levers, the former lever being adapted to be detained in its action by interference of said blocks until the stroke of the other lever is completed.
8. In combination with a reciprocating pump having a reversible gearing for actuating the same, a stop mechanism having contact relation with the pump to be actuated in opposite directions at the corresponding ends of the stroke of the pump; a detent mechanism having two oscillating shafts, each having in connection therewith a fixed lever, one of said shafts having means in connection with the stop mechanism to be actuated thereby and the other shaft having connection with the gearing adapted to reverse the same; a block on each of said levers extending in a common plane; a rod having sliding connection with each of the levers; and two springs on said rod acting respectively against said levers, the block on the lever actuated by the stop mechanism being adapted to engage the block on the other lever and thereby obstruct the movement of the latter lever during the transit of the former lever from one of its positions to the other.
9. In combination with the reciprocating pump and the reversible gearing for actuating the same, two oscillating shafts; a stop mechanism actuated by said pump in opposite directions at the corresponding ends of the stroke thereof; means in connection with one of the oscillating shafts for reversing said driving mechanism; and a detent mechanism having connection re-

spectively with said oscillating shafts adapted to obstruct the action of the latter oscillating shaft during the transit of the other oscillating shaft from one of its positions to the other.

10. In combination with a reciprocating pump having a reversible gearing for actuating the same and a stop mechanism actuated in opposite directions by said pump at the corresponding ends of its stroke, a detent mechanism comprised of two oscillating shafts, one having relation with the stop mechanism to be actuated thereby, and the other having means in connection with the gearing to reverse the same; a lever fixed on each of said shafts; a spud carried by each of said levers, a rod extending loosely through each of said spuds; two compression springs on the rod bearing upwardly against said spuds respectively; nuts on said rod adapted to rest against said spuds respectively upon the opposite side thereof to said springs; and a block fixed on each of said levers, extending in a common plane, the block on the lever actuated by the stop mechanism being adapted during the transit of the latter lever from one position to the other to obstruct the other block and thereby detain the movement of the other lever until the stroke of the former is completed.

11. In combination with a reciprocating pump, a reversible gearing having relation with the pump to actuate the same; a clutch-mechanism including a ratchet-wheel for driving the reversible gearing alternately in opposite directions accordingly as the ratchet-wheel is shifted; a stop mechanism adapted to be engaged and moved in opposite directions by the pump mechanism respectively at the ends of the stroke of the pump; and a detent mechanism for operating the ratchet-wheel and having driven relation with the stop mechanism.

12. In apparatus of the class described, a pump having a cylinder; a head for the cylinder at its discharge end having a chamber therein and an opening located above the bottom of the chamber for the admission of liquid from the cylinder into said chamber and having also an outlet opening; a removable screen having a plug with an opening therein removably fitted into the discharge opening of the head; and a discharge pipe secured in the opening of the plug and having communication with the chamber through said screen.

13. In apparatus of the class described, a reciprocating pump; a reversible driving gear for actuating the pump; a clutch mechanism with means in connection therewith for operating the driving gear; an oscillating shaft having an arm fixed thereon, the latter having a counter-sink near its outer end; a yoke loosely mounted upon the shaft and having loosely mounted therein

a spring pressed pointed plug extending into the counter-sink of the arm, said yoke having also connection with the clutch-mechanism to actuate the same; and a stop mechanism having operative relation with the pump mechanism and being adapted to oscillate said shaft.

14. In mechanism of the class described, a reciprocating pump mechanism; a reversible gearing having driving relation with said pump mechanism; and stop mechanism adapted to be engaged and actuated in opposite directions by the pump mechanism respectively at the ends of the stroke of the latter and having also actuating relation with the gearing to reverse the same.

15. In apparatus of the class described, a pump cylinder having a chamber-head at its discharge end, there being an opening in the head located above the bottom of the chamber therein for the passage of liquid from the pump-cylinder into the head, there being also an outlet aperture in the head; a plug having a discharge pipe in-connection therewith and extending therethrough, closing the discharge opening in the head from the exterior thereof; and a screen secured to the inner end of the plug and being removable therewith.

16. In apparatus of the class described, a reciprocating pump mechanism; a reversible gearing for actuating the pump mechanism and having a clutch device in connection therewith for controlling the same; an oscillating shaft; a yoke for actuating the clutch-device, having a spring pressed relation with the oscillating shaft through which the yoke is actuated upon oscillation of the shaft; and a mechanism having connection with the pump

mechanism and the oscillating shaft for actuating the latter in opposite directions at the respective ends of the stroke of the pump mechanism.

17. In apparatus of the class described, a reciprocating pump mechanism; a reversible gearing for actuating the pump mechanism; a stop mechanism actuated by the pump mechanism; an oscillating shaft having a segment gear thereon actuated by the stop mechanism; set screws oppositely disposed for limiting the movement of the oscillating shaft; and a detent mechanism actuated by the oscillating shaft and having operative relation with the gearing for reversing the latter.

18. In apparatus of the class described, a pump having a cylinder; a chambered head at the discharge end of the cylinder, there being an aperture in the head for the passage therethrough of fluid from the cylinder into the chamber located above the bottom of the chamber, said head having also an outlet opening therein at its top; a plug closing the outlet opening and being removable from the exterior thereof; a cup-shaped screen secured at its open end to said plug, its closed end extending within the chamber of the head to a point below the level of the inlet aperture therein; and a discharge pipe communicating through said plug and screen with the chamber in the head.

In testimony whereof I affix my signature, in presence of two witnesses.

LINNAEUS E. BAKER.
